MAGNETIC TRANSDUCER ADAPTED TO
COMPENSATE FOR TWISTING OF THE
RECORD WIREHoward E. Tompkins, Media, Pa., assignor, by
mesne assignments, to Philco Corporation,
Philadelphia, Pa., a corporation of Pennsylvania

Application September 6, 1945, Serial No. 614,739

18 Claims. (Cl. 179—100.2)

1

This invention relates to a magnetic wire recorder, and more specifically it relates to a system for reproducing transversely magnetized recordings upon a round wire in such a manner that the reproduced signals are unaffected by twisting of the wire on the longitudinal axis.

In recording intelligence upon a round wire by the transverse method of magnetization, a difficulty is encountered in the reproduction of the sound or other intelligence from the record on the wire because of the circular cross-section of the wire. This circular cross-section makes it possible for the wire to twist upon its longitudinal axis.

Consequently it is possible during reproduction for the wire to twist to such an extent that the magnetization of the wire is at right angles to the pick-up coil of the reproducer. Under these circumstances, the amplitude of the signal picked up may vary from full signal at no twist to no signal at a 90° twist of the wire.

Various arrangements have been suggested for overcoming such a difficulty. One such arrangement involves the use of automatic volume control in the amplifier, but this automatic volume control ceases to function when the wire has rotated a full 90° from the pick-up coil.

Another method which has been suggested for overcoming this difficulty employs an automatic follow-up system whereby the pick-up coils are caused to rotate around the longitudinal axis of the wire in synchronism with the twisting of the wire. Such a mechanism, while accomplishing the desired result, is subject to high maintenance cost and possible failure.

In my invention I use two pick-up magnetic structures oriented at right angles with respect to one another and at substantially the same location longitudinally on the wire which is to be run through the reproducer. The use of two such coils at right angles to each other insures that there always will be a signal available from the wire for if in one coil there is zero signal because the magnetism of the wire is oriented at right angles to the pick-up axis of the coil, then the other coil will receive a full signal.

In order to obtain an output from these two pick-up heads, it is necessary to find a method of combining the two voltages in such a manner that the combined signal will be substantially

2

independent of the orientation of the magnetic axis within the pick-up head structure. It can be shown that a simple addition of these two voltages will not suffice since under certain circumstances, with these two voltages added together directly, there will be a cancellation between the two and no signal will result from their combination.

I have discovered that in order to combine these two signals properly, one of the signals should be shifted in phase by 90° with respect to the other one. When this is done, the two resultant signals can be added together vectorially and their sum does not contain the orientation angle of the magnetic axis of the wire in such a way as to vary the amplitude of the signal obtained.

This means that regardless of the orientation of the wire, the output from the system has a constant amplitude if the magnetization of the wire is constant in amplitude. In other words, as the amplitude of magnetization of the wire varies, the output amplitude varies in the same proportion independently of the orientation of the magnetic axis of the wire on which the record has been recorded.

Consequently, an object of my invention is to provide a means for reproducing transverse magnetization upon a round wire in such a manner that there will be no interference or distortion resulting from random orientation of the magnetic axis of the wire.

Another object of my invention is to provide means for cancelling out the effect of twisting of a round wire in a magnetic recording.

Other objects of my invention will become apparent upon a study of the diagrams, in which

Figure 1 represents a schematic diagram of my pick-up head.

Figure 2 represents certain vector diagrams used in explaining the action of Figure 1.

Figure 3 is a block diagram of my invention.

Figure 4 represents phase shift curves obtained from the apparatus of Figure 3; and

Figure 5 is a detailed circuit diagram of the apparatus used to obtain the phase shift curves of Figure 4 and used in conjunction with my reproducing mechanism.

Referring now to Figure 1, the wire 101 is shown in cross-section. It is considered to be a long, thin, round wire whose length is perpen-

50

dicular to the plane of the drawing. In order to explain the operation of this device, the wire is represented as having magnetic poles impressed upon it, the north pole being represented by the reference letter N and the south pole being represented by the reference letter S.

The magnetic axis of the magnetic force impressed on the wire by the recording mechanism is at an angle θ with respect to a horizontal reference axis. The strength of these magnetic poles varies as the position is changed longitudinally along the wire and it is the variation in the strength of these magnetic poles which constitutes the recording upon the wire. The recording mechanism, which may be of any well known construction, is arranged to impress upon the wire variations in magnetic pole strength in accordance with desired signal recording.

The object of my invention is to satisfactorily reproduce the variations in magnetic pole strength independently of the angle θ .

In order to obtain signals from the magnetization of the wire 101, two magnetic structures 102 and 103 are used. Magnetic structure 102 is arranged at such an angle as to carry flux from the permanent magnetism of the wire 101 in the horizontal direction and magnetic structure 103 is similarly arranged to carry flux from the permanent magnetism in the vertical direction.

Each of these two magnetic structures is wound with a pick-up coil, structure 102 being wound with pick-up coil 104 and structure 103 being wound with pick-up coil 105. Variations in the magnetization of the wire 101 cause variations in the flux in the pick-up magnetic structures 102 and 103 and these variations in flux through coils 104 and 105 induce voltages in these coils. In order to more fully understand the operation of my invention, I have labeled these two voltages as E_1 and E_2 .

In Figure 2a, there is shown a simple construction for obtaining the magnitude of these two voltages E_1 and E_2 . The angle θ is plotted, as is indicated in this diagram, and a line for vector 106 is drawn at this angle with respect to the horizontal. Vector 106 has a length which is proportional to the voltage which would be introduced in one of the pick-up coils if it were oriented to be parallel to the magnetic axis of the wire. That is, if either one of the two pick-up coils were rotated so that the north and south poles of the magnetization on the wire were directly opposite the pole pieces of the magnetic structures, the voltages picked up in the coils would be proportional to the vector 106.

In Fig. 1, however, this arrangement is not carried out, and consequently the voltages induced in the two windings are proportional to certain functions of the angle θ . In particular, the voltage induced in the winding 104 is the maximum voltage multiplied by the cosine of angle θ . Correspondingly, the voltage induced in coil 105 is the maximum possible induced voltage multiplied by the sine θ . The construction of Figure 2 carries out this multiplication.

The magnitude of E_1 , represented by vector 107, is shown as the vertical projection of vector 106 and the magnitude of E_2 is shown as the horizontal projection 108 of vector 106.

It is to be understood that these two vectors 107 and 108 are not vectors in the sense that they represent vector quantities of E_1 and E_2 . Their lengths only are associated with E_1 and E_2 . The angles involved are drawn from the angles of orientation of the magnetic structure and wire,

and consequently the angles in Figure 2a correspond to angles in the mechanical structure and not to electrical angles.

In fact, the two voltages E_1 and E_2 are in phase with each other, and consequently when they are added together in Figure 2b, the direct addition of these two voltages E_1 and E_2 is shown. Here the total voltage is the sum of the two voltages and since both E_1 and E_2 are in phase with each other, the vectors representing E_1 and E_2 are drawn as co-linear vectors.

As the angle θ is varied, the two projections 107 and 108 shown in Figure 2a will vary in size. It can be shown that as these two vary, the sum of the two as shown in Figure 2b will also vary in size. In particular, if the angle θ should vary between 90° and 180°, it will be observed that the voltage E_2 will be reversed in phase. As a result, in Figure 2b, E_2 would turn out to be opposite in direction to E_1 and when the angle θ became 45°, the amplitude of E_2 would equal the amplitude of E_1 . Under this circumstance, the two would cancel and the sum of voltages E_1 and E_2 would then be zero. This would not be a satisfactory system for reproducing the recording on the wire; it would be no better than the use of a single pick-up coil.

In my invention I use electrical means to associate the amplitudes E_1 and E_2 with the angle θ in the same manner that the diagram of Figure 2a associates the two amplitudes and obtains therefrom the vector 106. The vector diagram of my invention is shown in Figure 2c. According to my invention, I cause vector E_1 to be shifted in phase from vector E_2 by 90°.

In carrying out this process, both vectors may be shifted in phase, but vector E_1 is shifted in phase 90° more than vector E_2 . Consequently, in Figure 2c, the vector E_1 after its phase shift, is represented by vector 109. This vector is called E_1' . Similarly, vector 110 represents voltage E_2 after having been shifted by the phase angle. This vector 110 is used to represent the voltage E_2' , which is voltage E_2 after its phase shift. The characteristics of the phase shift given to the two voltages, cause E_1' and E_2' to be out of phase with each other by 90°.

Under these circumstances, the vector addition of E_2' and E_1' is a vector 111. It is to be observed that this vector addition, shown in Figure 2c, is essentially similar to the process shown in Figure 2a whereby the two components E_1 and E_2 were obtained from the vector 106, which was the maximum possible voltage obtained from the wire by either coil independently.

As the angle θ is changed, the magnitudes of E_1 and E_2 in Figure 2a change. Likewise, the magnitudes of E_1' and E_2' in Figure 2c change accordingly with the result that Figure 2c always bears an essential similarity to Figure 2a. Consequently, vector 111 remains at a constant length for a constant input amplitude independent of the phase angle of θ . In fact, the angle 112 in Figure 2c is always the same as angle θ in Figure 2a.

A block diagram of the apparatus used in accomplishing my invention is shown in Figure 3. Here, pick-up coils 105 and 104 feed voltages E_1 and E_2 into phase shifters 112 and 113. Phase shifter 113 shifts the phase of E_1 by minus α degrees, giving the output voltage E_1' . Phase shifter 112 shifts the voltage E_2 by minus α minus 90°, giving voltage E_2' . Thus, voltage E_1 is 90° ahead of voltage E_2 . These two are added vectorially and fed into the amplifier 114, which in

turn feeds the loud-speaker 115. This loud-speaker is symbolic of any reproducing device which may be desired. Thus, in order to more thoroughly explain the action of my invention, I will make reference to certain equations, numbered 1 to 10, which follow in the description below.

Let the magnetization in the wire be represented by Equation 1.

$$\phi = \phi_m \sin \omega t \quad (1)$$

This equation can be thought of as the flux which would pass through one of the pick-up structures if the wire were so oriented that the maximum flux passed through this pick-up structure. The time variation represented by sine ωt is obtained by the longitudinal motion of the wire through the pick-up structure. In view of the random orientation of the wire, each of the pick-up coils will receive flux proportional to the appropriate functions of the angle θ . These two fluxes are indicated as ϕ_1 and ϕ_2 in Equations 2 and 3.

$$\phi_1 = \phi_m \sin \omega t \sin \theta \quad (2)$$

$$\phi_2 = \phi_m \sin \omega t \cos \theta \quad (3)$$

These are the fluxes which pass through the magnetic structures 102 and 103. From these fluxes, voltages are induced in the coils 104 and 105. Thus, in coil 105, the voltage induced is E_1 given by Equation 4 and in coil 104, the voltage induced is E_2 as given by Equation 5. In these equations, N is the number of turns in each coil, assuming them to be identical.

$$E_1 = N\phi_m \omega \cos \omega t \sin \theta \quad (4)$$

$$E_2 = N\phi_m \omega \cos \omega t \cos \theta \quad (5)$$

As has been mentioned before, the summation of these voltages directly is not useful in reproduction of the signals on wire 101. This is shown by Equation 6 in which is given the sum of E_1 and E_2 .

$$E_1 + E_2 = N\phi_m \omega \sqrt{2} \cos \omega t \sin(\theta + 45^\circ) \quad (6)$$

The last term in this equation, that is, the sine of $(\theta + 45^\circ)$ is obtained by mathematical processes from the appropriate Equations 4 and 5; that is, the sum of sine θ and cosine θ . It is recognized in mathematics that this function, sine of $(\theta + 45^\circ)$, varies between 0 and 1 depending upon the value of θ . Consequently, for specified values of θ , this function will be zero and no output voltage would result. This makes such a system of direct combination of the two coils totally impractical.

The output voltages of my phase shifters, however, do make a practical system. These output voltages are given in Equations 7 and 8.

$$E_1' = N\phi_m \omega \cos(\omega t - \alpha) \sin \theta \quad (7)$$

$$E_2' = N\phi_m \omega \cos(\omega t - \alpha - 90^\circ) \cos \theta \quad (8)$$

If E_1' is the voltage as shifted by phase shifter 113, and E_2' is the voltage as shifted by phase shifter 112, it is to be observed that the phase shifters cause the addition of the term $-\alpha$ and $-\alpha - 90^\circ$ in the functions involving ωt in these two equations.

With my invention, these two voltages E_1' and E_2' are added together. In order to make these two additions easy, it is first to be observed that the cosine curve involving ωt , Equation 8, is equivalent to a sine curve as is shown by Equation 9, which is an identity taken from trigonometry.

$$\cos(\omega t - \alpha - 90^\circ) = \sin(\omega t - \alpha) \quad (9)$$

Consequently, the sum of E_1' and E_2' , as given by Equation 10 is in a form which is recognized in trigonometry as being the expanded form of the sine of the sum of two angles.

$$E_1' + E_2' = N\phi_m \omega [\cos(\omega t - \alpha) \sin \theta + \sin(\omega t - \alpha) \cos \theta] \quad (10)$$

When this Equation 10 is collected into a more concise form by trigonometric transformation, Equation 11 results, in which the sum of the two angles E_1' and E_2' is given as the sine of $\omega t - \alpha + \theta$.

$$E_1' + E_2' = N\phi_m \omega \sin(\omega t - \alpha + \theta) \quad (11)$$

Inspection of this equation reveals that the angle θ enters in the equation only as a phase angle in the resultant voltages. It does not appear in such a way as to alter the amplitude of the resultant voltage. This is precisely the effect which I desired to obtain when I made my invention. It makes the invention a satisfactory one for reproducing sound from a recording made transversely on a round wire since the ear, which will be the ultimate interpreter of the reproduced sound, does not respond to variations in phase angle of a signal. Thus the inclusion of θ as a phase angle is unimportant in this system and will not cause distortion as far as the ear is concerned.

In another form of my invention I use a plurality of pick-up coils and a plurality of phase shifting networks so arranged that the phase shifts of the networks are correlated with the angular positions of the pick-up coils. For example, three pick-up coils arranged spatially at 60° intervals and three phase shifters designed for 60° phase angle differences provide an output independent of the twist of the wire.

Still another variation of my invention uses in place of the plurality of magnetic structures, a single magnetic structure built and wound in a manner similar to that employed in the construction of polyphase motor stators.

My invention has been described, heretofore, with respect to a single frequency of magnetization. However, it is well known that ordinary sound to be reproduced will be composed of a great number of frequencies. From the well-known principle of superposition, it will be found that a complicated sound may be considered to be made up of a summation of individual frequencies. Since the entire system here described is a linear system, the system will behave, in regard to each frequency component, just as it would behave with regard to that frequency independently of the presence of other frequencies.

In consequence of this, the output signal of the system will contain a great number of frequencies each being shifted by the phase angle θ and in addition, each being shifted by the phase angle minus α . In accordance with my invention, the phase angle α is different for each frequency and consequently each frequency component in the output will be shifted in phase from the corresponding frequency component in the input by a specified amount, which will be different from the phase shift for each other frequency component. This, however causes no difficulty since the ear is unresponsive to changes in the phase angle.

In order to accomplish the phase shift of 90° between the two signals E_1 and E_2 , the phase shifters 112 and 113 are designed in accordance with my invention as described in my co-pending patent application, Serial No. 613,457, filed August 30, 1945.

In accordance with this invention, I obtain a phase shift curve for phase shifter 113 in accordance with curve shown in Figure 4. Likewise, with respect to phase shifter 112, I obtain a phase shift in accordance with the curve of Figure 4.

It is to be observed that these two curves indicate a changing phase shift with respect to frequency over the whole frequency band, but that the essential characteristics of these two curves are that the phase angle differs between the two systems substantially 90° over the audio frequency band. This is shown as curve 24 which is the difference in phase between the two systems.

For theoretically perfect operation, this phase difference should be exactly 90° . However, if the phase angle varies by slight differences from 90° , there will be only a slight variation in the resultant amplitude, which will result in only slight variations in the output amplitude as angle θ varies. In consequence of this, the difference in phase shift between phase shifter 112 and phase shifter 113 need not be exactly 90° but may be between a range of approximately 10 degrees of 90° .

Thus, the network whose curves are shown in Figure 4, accomplishes this satisfactorily. This network which gives the curves shown in Figure 4 is shown in Figure 5. This shows a complete reproducing system, with pick-up coils, phase-shifting networks for combining the two signals, amplifier, and reproducing speaker.

In Figure 5, 101 energizes the two pick-up coils 104 and 105. One of these pick-up coils is fed into the top channel consisting of two bridge circuits 33 and 34, and a differential amplifier comprising vacuum tube 39, the output of which feeds into a differential amplifier composed of tubes 31 and 32.

The other pick-up coil feeds into the lower channel which is composed of phase shifting bridges 36 and 37 and a differential amplifier composed of tube 41, the output of which feeds into the differential amplifier composed of tubes 31 and 32.

These phase shifting channels are built in accordance with my invention described in co-pending application Serial No. 613,457, filed August 30, 1945. In the lower channel, for example, bridge 36 has a predetermined phase shift characteristic with respect to frequency. Bridge 37 has a similar, but different phase shift characteristic with respect to frequency; that is, its phase shift characteristic has a point of inflection at a different frequency than does bridge 36.

Since the two of these bridge networks are effectively connected in tandem in this circuit, their phase characteristics are additive. Consequently, the phase characteristic of the lower channel consisting of bridge 36 and bridge 37 together, is the sum of the individual phase characteristic of the two networks.

Such a curve is given, for example, by curve 20 in Figure 4. This curve is almost linear with respect to the logarithm of the frequency. The upper channel is so proportioned that it has the same type of curve for its phase shift curve, but it has this curve shifted in frequency to a higher frequency.

Accordingly, the curve of the upper channel in Figure 5 is shown in Figure 4 as curve 23. This is accomplished in the diagram by using smaller RC products in the upper channel than are used in the lower channel. Thus, for example, the

RC product in bridge 33 has a lower value than the RC product in bridge 36 and the RC product in bridge 34 has a lower value than the RC product in bridge 37. For all of these RC products the same ratio exists.

In these two networks, it can be observed that the amount of the frequency shift is approximately a factor of 5.3. This ratio can be seen readily from the curves of Figure 4. For example, at a phase angle of slightly more than -185° , the curve 20 crosses the 150 cycle mark. At the same value of angle, the curve 23 crosses the 800 cycle mark. Now the ratio of 800 cycles to 150 cycles is 5.3 approximately. This, then, is the ratio of the frequencies of the two curves. Consequently $R_1C_1=5.3R_2C_2$.

This ratio, of course, does not apply to capacitors such as 38, which are merely blocking capacitors and do not function in providing the phase shift in these networks. This ratio applies only to those capacitors in the bridge circuits themselves. The output circuit of Figure 5 is a conventional push-pull connection with a transformer and a loud-speaker connected into the secondary of the transformer.

In the description and specification which I have given for my invention above, I have described it with respect to a specific network. However, I do not wish it to be limited to a specific network; but instead, I prefer to have my invention described by the following claims.

I claim:

1. In a system for reproducing sound from a magnetized wire which is subject to arbitrary twists, two pick-up coils at substantially the same location longitudinally on the wire and arranged to be responsive to mutually perpendicular components of magnetic flux from said wire, the amplitude of the induced signals in said coils varying in accordance with said twists, two phase-shifting networks, one of said phase-shifting networks being fed from one of said pick-up coils and the other of said phase-shifting networks being fed from the other of said pick-up coils, said phase-shifting networks having phase characteristics which differ from each other by substantially 90° over a band of frequencies, and means for combining the output signals of said phase-shifting networks to produce a resultant signal which varies in amplitude in accordance with the magnetic recording on said wire and independent of any twist thereof.

2. In a system for the reproduction of sound from signals transversely recorded on a magnetized wire, two pick-up devices, each including a magnetic circuit and a coil linking said magnetic circuit, said pick-up systems being oriented to be responsive to magnetization at the same longitudinal location on said wire but to be responsive to mutually perpendicular components of magnetic flux set up by the magnetization of said wire, two phase-shifting networks, each having input and output terminals, the input terminals of one of said phase-shifting networks being connected to one of said pick-up devices, and the input terminals of the other of said phase-shifting networks being connected to the other of said pick-up devices, the output terminals of said phase-shifting networks being connected so as to provide a signal which is the sum of the output signals of said phase-shifting networks, and said phase-shifting networks having phase-shift characteristics which differ from each other by substantially 90° .

3. In a system for reproducing sound from a

magnetized wire of circular cross-section which is subject to arbitrary twists, pick-up coil means arranged to be responsive to magnetic flux from said wire at substantially the same location longitudinally on the wire, means including circuit connections to said pick-up coil means for producing from said flux two signals, one of the signals being shifted in phase substantially 90° with respect to the other, and means including circuit connections to said last circuit connection means for vectorially adding the resultant signals to produce a signal which is varied in accordance with the magnetization of said wire and independent of the orientation angle of the magnetism of the wire.

4. The method of reproducing sound from a magnetized wire which is subject to arbitrary twists, comprising generating two components from said flux, producing therefrom two signals, one of the signals being shifted substantially 90° with respect to the other, and adding the two signals vectorially.

5. In a system for reproducing sound from a magnetized wire of circular cross-section which is subject to arbitrary twists, pick-up coil means arranged to be responsive to magnetic flux from said wire at the same longitudinal location of said wire, means including circuit connections to said pick-up coil means for producing from said flux two signals, one of the signals being shifted in phase substantially 90° with respect to the other over a predetermined frequency range, and means including circuit connections to said last circuit connection means for vectorially adding the resultant signals to produce a signal which is varied in accordance with the magnetization of said wire and independent of the orientation angle of the magnetism of the wire.

6. The method of reproducing sound from a magnetized wire which is subject to arbitrary twists, comprising generating two components from said flux, producing therefrom two signals, one of the signals being shifted substantially 90° with respect to the other over a predetermined frequency range, and adding the two signals vectorially.

7. In a system for reproducing sound from a magnetized wire which is subject to arbitrary twists, two pick-up coils at right angles to each other at substantially the same location longitudinally on the wire and arranged to be responsive to component magnetic flux from said wire, means including circuit connections to said pick-up coils for producing from said flux two signals, one of the signals being shifted in phase substantially 90° with respect to the other, and means including circuit connections to said last circuit connection means for vectorially adding the resultant signals to produce a signal which is varied in accordance with the magnetization of said wire and independent of the orientation angle of the magnetism of the wire.

8. In a system for reproducing sound from a magnetized wire of circular cross-section which is subject to arbitrary twists, a pair of magnetic structures at substantially the same location longitudinally on the wire and one of said structures being arranged to pick up flux from said wire in the horizontal direction, and the other of said structures being arranged to pick up flux from said wire in the vertical direction, a coil wound in each of said structures and energized by the flux therein, a circuit connected to each of said coils, the signals in each of said circuits being substantially 90° in phase displacement

from each other, and a common circuit connected to the output of each of said first-mentioned circuits.

9. In a system for reproducing sound from a magnetized wire which is subject to arbitrary twists, a pair of magnetic structures at substantially the same location longitudinally on the wire and one of said structures being arranged to pick up flux from said wire in the horizontal direction, and the other of said structures being arranged to pick up flux from said wire in the vertical direction, a coil wound in each of said structures and energized by the flux therein, and means for generating a signal equal to the square root of the sum of the squares of the signals induced in each of said coils.

10. In a system for reproducing sound from a magnetized wire which is subject to arbitrary twists, two pick-up coils at substantially the same location longitudinally on the wire and arranged to be responsive to predetermined components of magnetic flux from said wire, the amplitude of the induced signals in said coils varying in accordance with said twists, two phase-shifting networks, one of said phase-shifting networks being fed from one of said pick-up coils and the other of said phase-shifting networks being fed from the other of said pick-up coils, said phase-shifting networks having phase characteristics which differ from each other by said predetermined angle over a band of frequencies, and means for combining the output signals of said phase-shifting networks to produce a resultant signal which varies in amplitude in accordance with the magnetic recording on said wire and independent of any twist thereof.

11. In a system for the reproduction of sound from signals transversely recorded on a magnetized wire of circular cross-section, two pick-up devices at substantially the same location longitudinally on the wire and each including a magnetic circuit and a coil linking said magnetic circuit, said pick-up systems being oriented to be responsive to magnetization at the same longitudinal location on said wire but to be responsive to predetermined components of magnetic flux set up by the magnetization of said wire, two phase-shifting networks, each having input and output terminals, the input terminals of one of said phase-shifting networks being connected to one of said pick-up devices, and the input terminals of the other of said phase-shifting networks being connected to the other of said pick-up devices, the output terminals of said phase-shifting networks being connected so as to provide a signal which is the sum of the output signals of said phase-shifting networks, and said phase-shifting networks having phase-shift characteristics which differ from each other by said predetermined angle.

12. In a system for reproducing intelligence from a magnetized wire which is subject to arbitrary twists, a pair of magnetic structures at substantially the same location longitudinally on the wire and arranged to carry mutually perpendicular components of flux from said wire, a coil wound in each of said structures and energized by the flux therein, and means for generating a signal equal to the square root of the sum of the squares of the signal induced in each of said coils.

13. The method of reproducing intelligence from a magnetized wire which is subject to arbitrary twists, comprising generating a plurality of components from said flux, producing therefrom

11

a plurality of signals, said signals being shifted in phase with respect to one another by electrical angles which are substantially the same as the mechanical angles of said components of said flux, and adding said signals vectorially.

14. A reproducer for magnetic recordings where the recorded signal is recorded magnetically transversely of the recording medium comprising a pair of signal channels having input and output terminals for transmitting signals of the same frequency to the same extent; means for modifying the phase of signals passing through one of said channels relative to the phase of signals passing through the other of said channels to a predetermined extent; means connected to said output terminals for combining the output signals of said channels; magnetic signal pick-up devices for individually applying signals of the same frequency to the inputs of said channels; said pick-up devices being located in the same plane, transverse to the direction of motion of the recording medium, and being angularly related with respect to each other by an angle substantially less than one hundred and eighty degrees; and circuit connections for producing the same output signal regardless of the instantaneous rotary orientation of the magnetic signal in the wire, said circuit connections comprising means for maintaining constant the relative phase angle between the signals at the output terminals of said channels regardless of the frequency of said signals.

15. A reproducer for magnetic recordings where the recorded signal is recorded magnetically transversely of the recording medium comprising a pair of signal channels having input and output terminals for transmitting signals of the same frequency to the same extent; means for modifying the phase of signals passing through one of said channels relative to the phase of signals passing through the other of said channels to a predetermined extent; means connected to said output terminals for combining the output signals of said channels; magnetic signal pick-up devices for individually applying signals of the same frequency to the inputs of said channels; said pick-up devices being located in the same plane, transverse to the direction of motion of the recording medium, and being angularly related with respect to each other by an angle substantially less than one hundred and eighty degrees; and circuit connections for producing the same output signal regardless of the instantaneous rotary orientation of the magnetic signal in the wire, said circuit connections comprising means for maintaining a substantially ninety degree phase angle between the signals at the output terminals of said channels regardless of the frequency of said signals.

16. A reproducer for magnetic recordings where the recorded signal is recorded magnetically transversely of the recording medium comprising a pair of signal channels having input and output terminals for transmitting signals of the same frequency to the same extent; means for modifying the phase of signals passing through one of said channels relative to the phase of signals passing through the other of said channels to a predetermined extent; means con-

12

nected to said output terminals for combining the output signals of said channels; magnetic signal pick-up devices for individually applying signals of the same frequency to the inputs of said channels; said pick-up devices being located in the same plane, transverse to the direction of motion of the recording medium, and being effectively ninety degrees with respect to each other; and circuit connections for producing the same output signal regardless of the instantaneous rotary orientation of the magnetic signal in the wire, said circuit connections comprising means for maintaining constant the relative phase angle between the signals at the output terminals of said channels regardless of the frequency of said signals.

17. In a reproducer for magnetic recordings on a wire, a pair of pick-up magnetic structures oriented at right angles with respect to one another and at substantially the same location longitudinally on said wire, circuit arrangement for shifting the signal outputs of said structures substantially 90° with respect to each other, said circuit arrangement including a first phase shifter connected to the output of one of said structures for shifting the signals through an angle $-\alpha$, and a second phase shifter connected to the output of the other of said structures for shifting the signals through an angle $-\alpha-90^\circ$, and a common output circuit for said phase shifters in which the resultant signals are added vectorially.

18. In a reproducer for magnetic recording on a wire, a pair of magnetic pick-up structures, one of said magnetic structures being arranged to pick up one component of the signal on the wire equal to the signal which would be induced in one of the structures if said one of the structures were oriented to be parallel to the magnetic axis of the wire multiplied by the cosine of the angle of orientation of the structure to the magnetic axis of the wire, and the other structure being arranged to pick up the other component making up the signal on the wire equal to the signal which would be induced in one of the structures if said one of the structures were oriented to be parallel to the magnetic axis of the wire multiplied by the sine of the angle of orientation of the structure to the magnetic axis of the wire, individual circuit arrangements connected to the output of each of said structures, said circuit arrangement shifting the phase of the output signal substantially 90° electrical degrees with respect to each other, and a common output circuit for said individual circuit arrangement for vectorially adding the signals in each of said circuit arrangements.
